CONTROL DEVICE FOR CONTINUOUS SPINNING AND TWISTING FRAMES

Mathieu Henri Herman Marie Ghislain Fischer,
Heusy-Verviers, Belgium, assignor to Ateliers
Houget, Societe Anonyme Vervietoise pour la
Construction de Machines, Vervieres, Belgium,
a Belgian company

Application April 23, 1947, Serial No. 743,376
In Belgium December 17, 1941

Section 1, Public Law 690, August 8, 1946
Patent expires December 17, 1961

10 Claims. (Cl. 57—93)

1

My invention relates to improvements in continuous spinning and twisting machines of the type in which the feed rollers are driven at a speed in direct proportion to the count of the yarn and has for its object to render more easy the control of the twist.

According to the present invention, feed rollers and spindles are driven in parallel from a common shaft through two variable speed devices positively coupled by their control wheels so that a shaft driven by one variable speed device rotates at maximum speed when a shaft driven by the other variable speed device rotates at a minimum speed.

The invention will be described with reference to the accompanying drawings:

Figure 1 is a diagrammatic end elevation of a spinning frame.

Figure 2 is a transverse section of same.

Sliver is fed to the feed rollers 1 driven by a following drawing roller 2 through a gear train 6, 7, 8, 9, 10, 11 and 12 with a series of change wheels 9 from a motor driven shaft 13 driving a shaft 28 in a variable speed device 18.

A table indicates the pinion 9 or change sprocket to be employed for obtaining a predetermined feed roller speed less than that of the drawing roller 2 to give the required draft to the yarn.

The spindle 3 is also positively driven from the motor shaft 13 through a further positive transmission 31 driving a fluted drum or tin roller 32 over which spindle bands 31' driving the spindles 3 pass. A shaft 29 in a variable speed device 19 is geared to a shaft 221.

The drive for the feed to the spindles comprises a chain 14 passing over sprockets 15, 16 and over a tension sprocket 17 and driving shaft 16' coupled to the shaft 28. The rotary drive for the spindles comprises a chain 20 passing over sprockets 21—21 and tension sprocket 23 driving the shaft 221.

The drive for the drawing rollers 2 and the spindles 3 are thus positively coupled together in parallel from the motor shaft 13.

In the variable speed device 18, the driving shaft 16' and the driven shaft 28 are in relation together through the medium of an intermediary shaft 34 on which is fixed a control wheel 25 and carrying an indicator disc 27 cooperating with an index 33.

In the variable speed device 19, the driving shaft 221 and the driven shaft 29 are in relation together through the medium of an intermediary

2

shaft 35 on which is keyed a control wheel 24 bodily connected with an indicator disc 36.

The two variable speed devices 18—19 are coupled together permanently by their control wheels 24—25 through a positive transmission constituted by a crossed belt 26.

Therefore when the indicator disc of one of the variable speed devices is operated, for example the disc 27 which may be bodily connected with the control wheel 25, a maximum speed will be obtained for the driven shaft 28 with a minimum speed for the driven shaft 29 and vice-versa.

The variable speed devices 18 and 19 may be of any suitable kind. The connection between shaft 16', 28 and 221—29 respectively may be constituted for instance by a system of belts and expandable or extensible pulleys.

It therefore follows that the indicator disc 27 (Fig. 1) will give at the commencement of the graduations of that speed gear a maximum feed for a minimum number of turns of the spindles; that operation of the disc in the direction of the graduations from the index 33 will decrease the feed and at the same time increase the number of rotations of the spindles. At the end of the operation when the index 33 will be reached with the last graduation, the feed will be a minimum and the number of rotations of the spindles a maximum.

In other words these two variables are none other than the quotient determining the theoretical twist given by the ratio:

Theoretical twist=

$$35 \quad \frac{\text{number of turns per minute of the spindle}}{\text{feed in metres—minutes}}$$

The disc 27 may therefore be graduated directly in terms of twist.

40 By suitable angular displacement of the graduations from their theoretical position the disc 27 may be inscribed directly in actual twist very closely this twist being given by the ratio:

Actual twist=

$$45 \quad \frac{\text{number of turns of the thread about itself}}{\text{number of metres of thread twisted}}$$

The arrangement according to the invention thus does away with the series of revolution counters and tachometers which are necessary in the known modern constructions as hereinbefore described this omission enabling the control heads for the twist to be eliminated.

50 The optimum speed of production will be given by the motor shaft 13 (Fig. 1).

In the arrangement according to the present invention, the end of the drawing roller 2 may be coupled by means of a belt 31 with a pulley 38 keyed on a shaft 39 carrying a tachometer T combined with a totalizing revolution counter and a secondary zero resetting means.

What I claim is:

1. In a continuous spinning frame, an arrangement for general control and adjustment of the twist comprising two variable speed governing devices, one for the control of the feed roller and the other for the control of the spindle drum, each governing device being provided with a controlling wheel, a motor shaft, means driving said governing devices in parallel from said motor shaft, and means connecting the controlling wheels of the speed governing devices, said last named means being formed and arranged to cause the driven shaft of one governing device to rotate at its maximum speed while the driven shaft of the other governing device rotates at its minimum speed, and vice versa.

2. In a continuous spinning frame, an arrangement for the general control and adjustment of the twist comprising two variable speed governing devices, one for the control of the feed roller and the other for the control of the spindle drum, each governing device being provided with a controlling wheel, a motor shaft, means driving said governing devices in parallel from said motor shaft, means connecting the controlling wheels of the speed governing devices, said last named means being formed and arranged to cause the driven shaft of one governing device to rotate at its maximum speed while the driven shaft of the other governing device rotates at its minimum speed, and vice versa, a drawing roller preceding the feed roller, and means controllingly connecting said drawing roller to the feed roller.

3. In a continuous spinning frame, an arrangement for the general control and adjustment of the twist comprising two variable speed governing devices, one for the control of the feed roller and the other for the control of the spindle drum, each governing device being provided with a controlling wheel, a motor shaft, means driving said governing devices in parallel from said motor shaft, means connecting the controlling wheels of the speed governing devices, said last named means being formed and arranged to cause the driven shaft of one governing device to rotate at its maximum speed while the driven shaft of the other governing device rotates at its minimum speed, and vice versa, a drawing roller preceding the feed roller, and means controllingly connecting said drawing roller to the feed roller, said latter means comprising change pinion means formed and arranged for obtaining a predetermined drawing roller speed less than the speed of the feed roller to give a desired draft to the yarn.

4. In a continuous spinning frame, an arrangement for the general control and adjustment of the twist comprising two variable speed governing devices, one for the control of the feed roller, and the other for the control of the spindle drum, each governing device being provided with a controlling wheel, a motor shaft, means driving said governing devices in parallel from said motor shaft, means connecting the controlling wheels of the speed governing devices, said last named means being formed and arranged to cause the driven shaft of one governing device to rotate at its maximum speed while the driven shaft of the

other governing device rotates at its minimum speed and vice versa, a drawing roller preceding the feed roller, means controllingly connecting said drawing roller to the feed roller, a fluted roller, and means controllingly connecting said fluted roller to the drawing roller.

5. In a continuous spinning frame, a fluted roller, a driving mechanism for said fluted roller, drawing rollers, a driving mechanism for said drawing rollers, feed rollers, a driving mechanism for said feed rollers, said mechanisms being arranged in series, a motor shaft, means coupling the mechanisms, said means being formed and arranged to cause each mechanism to be driven from the mechanism which follows it, and an arrangement for the general control and adjustment of the twist, comprising two variable speed governing devices, one for the control of the feed rollers and the other for the control of the fluted roller, each governing device being provided with a controlling wheel, means driving said governing devices in parallel from said motor shaft, and means connecting the controlling wheels of the speed governing devices, said last named means being formed and arranged to cause the driven shaft of one governing device to rotate at its maximum speed while the driven shaft of the other governing device rotates at its minimum speed and vice versa.

6. In a continuous spinning frame, an arrangement for the general control and adjustment of the twist comprising two variable speed governing devices, one for the control of the feed roller and the other for the control of the spindle drum, each governing device being provided with a controlling wheel, a motor shaft, means driving said governing devices in parallel from said motor shaft, means connecting the controlling wheels of the speed governing devices, said last named means being formed and arranged to cause the driven shaft of one governing device to rotate at its maximum speed while the driven shaft of the other governing device rotates at its minimum speed and vice versa, a first non-adjustable transmission connecting the feed roller to the driven shaft of one of the speed governing devices, and a second non-adjustable transmission connecting the spindle drum to the driven shaft of the other speed governing device.

7. In a continuous spinning frame, an arrangement for the general control and adjustment of the twist comprising two variable speed governing devices, one for the control of the feed roller and the other for the control of the spindle drum, each governing device being provided with a controlling wheel, a motor shaft, means driving said governing devices in parallel from said motor shaft, means connecting the controlling wheels of the speed governing devices, said last named means being formed and arranged to cause the driven shaft of one governing device to rotate at its maximum speed while the driven shaft of the other governing device rotates at its minimum speed and vice versa, and an indicator disc carried by the control wheel of one of the variable speed governing devices, said indicator disc being graduated directly in twist, expressed in turns per unit length.

8. In a continuous spinning frame, an arrangement for the general control and adjustment of the twist comprising two variable speed governing devices, one for the control of the feed roller and the other for the control of the spindle drum, each governing device being provided with a controlling wheel, a motor shaft, means driving said

governing devices in parallel from said motor shaft, means connecting the controlling wheels of the speed governing devices, said last named means being formed and arranged to cause the driven shaft of one governing device to rotate at its maximum speed while the driven shaft of the other governing device rotates at its minimum speed, and vice versa, an indicator disc carried by the control wheel of one of the variable speed governing devices, said indicator disc being graduated directly in twist, expressed in turns per unit length, a tachometer coupled to the feed roller, and a double revolution counter also coupled to the feed roller, said revolution counter having one counting element which indicates total revolutions and another counting element which is resettable to zero, whereby the instantaneous speed of the feed roller, the total movement of the feed roller, and the movement of the feed roller during a predetermined interval may be observed.

9. A drive for a continuous spinning and twisting machine, comprising feed rollers, two variable speed devices, spindles, a shaft, means formed and arranged to drive said feed rollers and spindles from said shaft through said variable speed

5

devices, said variable speed devices each being provided with a control wheel, and means connecting the control wheels, said last named means being formed and arranged to cause a driven shaft of one variable speed device to rotate at maximum speed while a driven shaft of the other variable speed device rotates at minimum speed.

10. A drive for a continuous spinning and twisting machine according to claim 9, in which the control wheel for one of the variable speed devices is provided with a disc graduated directly in twist, expressed in turns per unit of length.

MATHIEU HENRI HERMAN
MARIE GHISLAIN FISCHER.
